US0D1018733S

(12) **United States Design Patent** (10) **Patent No.:** **US D1,018,733 S**
(45) **Date of Patent:** **** Mar. 19, 2024**

(54) **BARBELL WEIGHT CLAMP**

(71) Applicant: **LC Fitness, LLC**, Wilmington, DE (US)

(72) Inventor: **Jess Cardona**, Manila (PH)

(73) Assignee: **LC Fitness, LLC**, Wilmington, DE (US)

(**) Term: **15 Years**

(21) Appl. No.: **29/897,105**

(22) Filed: **Jul. 11, 2023**

(51) **LOC (14) Cl. 21-02**

(52) **U.S. Cl.**

USPC **D21/694**

(58) **Field of Classification Search**

USPC D21/681, 694, 679, 839; D8/369, 331, D8/399, 394; D13/152, 154; D23/265

(57) **CLAIM**

I claim the ornamental design for a barbell weight clamp, substantially as shown and described.

DESCRIPTION

FIG. 1 is an upper side perspective view of a barbell weight clamp showing my new design in a closed position;

FIG. 2 is a lower side perspective view thereof;

FIG. 3 is a right side view thereof, the left side being a mirror image of the right side;

FIG. 4 is a rear view thereof;

FIG. 5 is a front view thereof;

FIG. 6 is a top view thereof;

FIG. 7 is a bottom view thereof;

FIG. 8 is an upper side perspective view of the barbell weight clamp showing my new design in an open position;

FIG. 9 is a lower side perspective view thereof;

FIG. 10 is a right side view thereof, the left side being a mirror image of the right side;

FIG. 11 is a rear view thereof;

FIG. 12 is a front view thereof;

FIG. 13 is a top view thereof; and,

FIG. 14 is a bottom view thereof.

1 Claim, 10 Drawing Sheets
